UNITED STATES PATENT OFFICE.

JOSEPH BURTON, OF NEW YORK, N. Y., ASSIGNOR TO WILLIAM H. DOWN, OF SAME PLACE, AND WILLIAM N. MILSTED, OF BROOKLYN, NEW YORK.

GAS-BURNER FOR HEATING PURPOSES.

SPECIFICATION forming part of Letters Patent No. 284,814, dated September 11, 1883.

Application filed April 7, 1883. (No model.)

To all whom it may concern:

Be it known that I, JOSEPH BURTON, of the city and county of New York, in the State of New York, have invented certain new and useful Improvements in Gas-Burners for Heating Purposes, of which the following is a specification.

This invention relates more especially to burners which have large surfaces, and from which the gas and air issue through numerous orifices.

The invention consists in the combination, with a gas-heating burner consisting of a chamber having great horizontal area and but little thickness, and one of the horizontal walls of which is perforated, of a horizontally-extending distributer within the chamber, which receives gas from the supply-pipe, and which is provided around its sides with numerous perforations, through which gas is delivered in fine jets or streams against the surface of the chamber, which is opposite the perforated wall thereof. By the use of this distributer the gas is expanded as it issues from the supply-pipe, and is then delivered in fine jets or streams into the burner-chamber, where it is again further expanded.

The invention also consists in a novel construction of the distributer, whereby the cost of manufacture is lessened.

In the accompanying drawings, Figure 1 represents a longitudinal section illustrating the application of my invention to a flat burner, such as that described in patent to A. W. Morton, No. 238,301, March 1, 1881. Fig. 2 is a transverse section of the same through $x x$ of Figs. 1 and 3. Fig. 3 is an inverted plan of the upper part of the burner, showing the interior of the upper surface and the distributer. Fig. 4 is a plan view illustrating my invention as applied to a burner of the kind described in patent to A. W. Morton, No. 220,490, October 14, 1879, a portion of the upper part of the burner being broken away to expose the distributers to view. Fig. 5 is a transverse vertical section through the line $y y$ of Fig. 4. Fig. 6 is a longitudinal section illustrating my invention as applied to a straight or tubular burner.

The burners represented in Figs. 1, 2, and 3, which I will first describe, are of oblong rectangular form, and are shown as having but one inlet, more than one being rendered unnecessary by my distributer.

50
A is the crimped or corrugated lower plate of the burner, and b are the jet-orifices in the same. C is the upper part of the burner, which is secured to the plate A in any appropriate manner—as, for example, by screw-bolts d . The upper part, C, is so constructed with a top crown, e , and side and end walls, f , that there will be a free space or chamber, F, between A and C, for the distribution and diffusion of the gas. G is the inlet-pipe which admits the gas to the burner. To the under surface of the crown e , at the gas-inlet G, is attached the distributer h . This distributer is of a form somewhat resembling an inverted bridge. It is closed at the end i , which is opposite to the inlet G, and has numerous notches, $j j$, in its upper edges, which form side openings in its upper part, close to the crown e , for the gas to pass through and for its distribution against the whole interior of said crown, whence it will diffuse itself through the chamber F before passing to the jet-orifices, whence it will be delivered in uniform quantity throughout the whole face of the burner. As the distributer h is formed, and before it is attached to the wall C of the burner, it consists simply of a bottomless shell with notched edges.

70
The burner represented in Figs. 4 and 5 is of double ring form, and has two inlets—one, O, for the ring or annular chamber N, and one, O', for the ring or annular chamber N'. These two hollow rings or chambers N N' are represented as composed of a bottom plate, K, and a top plate, L. $m m$ are the jet-orifices, which are in the top of the burner, instead of in the bottom thereof, as in Figs. 1, 2, and 3. P and P' are the distributers—one for each chamber or ring N N'. They are of bridge-like form, and curved so as to fit within said rings, and instead of the openings $j j$ being in the upper portion of the burner, as in Figs. 1, 2, and 3, the said openings are adjacent or near to the bottom K, in order that the gas may be distributed against the whole bottom surface of

and thus diffused through the chambers N and N' before passing to the jet-orifices *m*.

In Fig. 6 the burner is composed of a long straight horizontal tube, Q, having the jet-orifices *q* in its top. R is the gas-inlet pipe, which admits the gas into the bottom of the chamber of the burner, which is the interior of the tube Q. S is the distributor, which is placed opposite the gas-inlet. This distributor is somewhat similar to that represented in Figs. 1, 2, and 3, being of the form of a bridge covering the inlet R, but having its openings or notches *j j* adjacent or near to the bottom of the burner, so that the gas will be distributed over the bottom of the chamber or tube Q, and so diffused uniformly through the entire chamber before it passes to the jet-orifices *q*.

Instead of the small openings or notches *j j* in the distributor, there may be a long, narrow, longitudinal slit or opening, when, instead of the gas passing through said distributor in small streams, it will pass through in a thin continuous sheet in close contact with the surface opposite the issue-orifices.

It may be understood from the above description and the annexed drawings that the position of the distributor and its openings *j j* is in all cases such that the gas entering the chamber of the burner through numerous orifices or through a very narrow channel or channels close to that surface which is opposite to the jet-orifices, and therefore before passing to said jet-orifices, whether they are in the upper or the lower part of the burner, the gas is thoroughly distributed and diffused through the whole chamber.

Instead of the openings of the distributor being made in its edges, so as to come absolutely close to that surface of the interior of the chamber of the burner opposite the issue-orifices of the latter, the said openings may be made in the sides of the distributor, provided that they have such a direction that the gas issuing from them will impinge on the aforesaid surface.

In all forms of my invention herein shown and described, the burner-chamber has a large horizontal area, and is of but little thickness, and the distributor extends horizontally. The

gas entering the distributor is expanded there-in, and in such expanded condition issues in numerous fine jets or streams into the burner-chamber, where it is still further expanded before it reaches the perforations of the burner.

I am aware that it is not new to close the end of a pipe for supplying gas to a heating-burner and to perforate the pipe laterally for the escape of gas into the burner; and I am also aware that it is not new to extend the supply-pipe into the central portion of a burner-chamber and to provide it with outlets for delivering gas in opposite directions against the imperforate walls of the burner-chamber. I do not claim either of the above-described constructions as of my invention.

Having now described my invention, what I claim as new, and desire to secure by Letters Patent, is—

1. The combination, with a gas heating-burner consisting of a chamber having great horizontal area and but little thickness, and one of the horizontal walls of which is perforated, of a horizontally-extending distributor within the chamber, which receives gas from the supply-pipe, and which is provided around its sides with numerous perforations or apertures, through which the gas is delivered in fine jets or streams against that surface of the chamber which is opposite the perforations, substantially as and for the purposes described.

2. The combination, with a gas heating-burner consisting of a chamber having great horizontal area and but little thickness, and one of the horizontal walls of which is perforated, of a horizontally-extending distributor receiving the gas from the supply-pipe, and consisting of a bottomless shell or bridge secured against the surface of the chamber which is opposite the perforations, and provided in the edge bearing against said surface with numerous notches, forming apertures for the passage of gas into said chamber, substantially as and for the purpose described.

JOSEPH BURTON.
